CLAIM

The ornamental design for a bullet-shaped connector casing, as shown and described.

DESCRIPTION

FIG. 1 is a top, front perspective view of a bullet- shaped connector casing, showing my new design;

FIG. 2 is a front elevation view thereof;

FIG. 3 is a side elevation view thereof; and,

FIG. 4 is a rear elevation view thereof.

The broken line showing of the environment is for illustrative purposes only and forms no part of the claimed design.
